UNITED STATES PATENT OFFICE.

DAVID R. KNAPP, OF PHILADELPHIA, PENNSYLVANIA.

DEVICE FOR ELECTRICALLY OPERATING BULKHEAD-DOORS.

No. 852,724.

Specification of Letters Patent.

Patented May 7, 1907.

Application filed August 27, 1906. Serial No. 332,174.

To all whom it may concern:

Be it known that I, DAVID R. KNAPP, a citizen of the United States, residing in the city and county of Philadelphia and State of Pennsylvania, have invented certain new and useful Improvements in Devices for Electrically Operating Bulkhead-Doors, &c., of which the following is a specification.

My invention relates to electro mechanical contrivances employed for closing, from one or more central stations, the various bulkhead and deck doors on ships, and the means for reopening the same; and the object of my said improvement is to provide a method for controlling the closing of the electric current circuits by which the motors that actuate the movement of the doors are put in operation in succession, either singly or in sets as may be desired, by means of a single main electric current circuit that is common to all the motors, in order that the desired result may be accomplished with less amount of current transmission wiring and a less capacity of electric current generator than heretofore required for said purpose. I accomplish said object by the method and apparatus hereinafter described and specifically mentioned in the claims that are hereto appended and form a part hereof.

The nature, characteristic features, and scope of my said invention will be more fully understood from the following description, taken in connection with the accompanying drawings, forming part hereof, and in which Figure 1 is a view diagrammatically illustrating a unit installation of my said invention.

Referring to the drawings, 1 indicates a bulk-head or a deck door provided with means, which is no part of my said invention, for being opened and closed through the operations of an electric current series motor, indicated by 2; the line or main circuit by which current for operating the motor is supplied is indicated by 3 and 4; 5 represents the electric current generator or source of electric current supply; 6 represents a rheostat by which a variable voltage circuit is provided through the leads 7 and 4 for operating electric-magnets which are connected in parallel in separate circuits for closing the motor circuits, as hereinafter described; the branch motor circuits, when closing the door from a central station, is composed of the leads 12, 13, 14, 15, 16, 17, 18 and 19, the direction of the current flow being in that

of the order in which the leads are here mentioned; in case of opening the door electrically, which is accomplished by means of the local rheostat 23, the rotation of the motor 60 armature is reversed by reversing the polarity of its fields; this is accomplished by shifting the contacts of the pole-changer 20, when the motor circuit is then composed of leads 12, 13, 15, 14, 16, 24 and 19, the direction of 65 the current flow being in that of the order in which the leads are here mentioned.

The means employed for closing the motor circuits in successive control, from a central station, consists of the electro-magnet 8 energized by the variable voltage line or main circuit 7, 4, which is connected to the magnet through the leads 21 and 22. The magnet 8 is provided with a weighted armature 9 which is supported in a movable position 70 by the rod 25 one end of which is attached to the core of the magnet and the other end is threaded and provided with a nut 26 for the purpose of enabling an adjustment of the width of the air-gap between the magnet-armature and the magnet-core. The magnet is also provided with insulated contact points 75 10 and 11, interposed between the leads 17 and 18 of the motor circuit, as shown; the magnet-armature is provided with an insulated contact-ring 27, for closing the leads 80 17 and 18 through the contact points 10 and 11.

As a magnet will lift different loads under different degrees of magnetism it is obvious 90 that with a variable voltage circuit for energizing it its armature 9, being so adjusted as to afford a constant width of air-gap, can then be varied, by means of a variation in its weight, to close the contacts 10 and 11 only 95 under that voltage in its energizing circuit that is proportioned for a corresponding weighted armature; the weighting of the armature, of course, being proportionate to suit the different voltages afforded by the 100 different resistances of the rheostat 6. It is also obvious that like control can be had by having the weight of the magnet-armature a constant and varying the width of the air-gaps of the different magnets; also that a like control 105 by the use of a combination of armatures of different weights in conjunction with a variation in the width of the air-gaps, can be obtained by the use of my herein-described invention.

The arrangement of the magnet-armature shown in the detail illustration Fig. 2 in-

dicates the manner of varying the weight of same, the disks 28 being made of such weight and added to the armature in such numbers as the conditions as to the number of doors or sets of doors it may be desired to have under the control of a central station.

For the purpose of breaking the motor circuit upon the closing of a door a projecting arm 29 is provided on the door so as to engage with the contact-lever 30, at the proper time in the door movement, thereby separating the insulated contact point 31 from the point 32 upon the door arriving at its closed position. The opening of the contacts 31 and 32 breaks or opens the energizing circuit of the magnet, thus terminating its attractive force on the armature 9 and allows it to drop to its normal open position of the contacts 10 and 11 and thereby opening the motor circuit, and stopping the motor.

The lever 30 is pivoted and weighted so that its contact point 31 will be held in its closed position by gravity against contact 32; or the same result may be obtained by the use of a spring where conditions may make such device preferable to that of gravity.

The resistance 33 is inserted in the motor circuit for the purpose of enabling the opening or closing of any individual door locally and independent of the central station, through the use of the rheostat 23 which is inserted in shunt with the magnet 8 and resistance 33, and is operated in conjunction with the pole-changer 20 provided for that purpose and located as shown.

The operation of my said invention is as follows:—It being assumed that a number of doors are equipped with the contrivances herebefore described, and that they are respectively connected and adjusted with a view to closing the doors in succession from a central station, the contact-arm of the rheostat 6 is placed on that contact the resistance of which will afford a voltage in the line 7, 4, that is a small fraction, say ten per centum, of that in the constant voltage circuit 3, 4; therefore that magnet or series of magnets, and those only, which has or have its or their armature or armatures so adjusted as to close the contacts 10 and 11 under that voltage will respond, thereby closing the motor circuit or circuits and causing the motor, or motors to close its or their respective door or doors. As the maximum load on the generator occurs only at the moment of starting the closing movement of the doors it is obvious that the next door or series of doors may be started to close so soon as the first door or series of doors are started, thereby obviating the use of a generator of capacity sufficient to provide current for a simultaneous starting of all the doors at the same contact of the operating device.

To start the closing of the next door or

series of doors the rheostat-arm is placed on the next resistance which affords a larger per centum of the total voltage, say twenty per centum, whereupon those magnets, and those only, (as those of the lower voltage adjustment having acted their respective door positions maintain an open energizing circuit and therefore those magnets will not respond to the then higher voltage with which the main energizing circuit is charged), having their armatures adjusted to suit the increased voltage will respond and close their motor circuits; and so on, step by step, until all the doors are closed, the number of steps, of course, being graduated to suit the range of variable voltage attainable for the purpose, and contrariwise, the number of variations in the voltage being proportioned to meet the requirements as to the number of doors or sets of doors to be closed from any one central station.

Having thus described the nature and object of my said invention, what I claim as new, and desire to secure by Letters Patent, is:—

1. In a system of electric current control, in combination, a positive lead transmitting a constant voltage current; and a positive lead transmitting a variable voltage current; and a negative lead, common to said constant and variable voltage leads and completing their respective circuits; and a distribution circuit connected across said constant voltage line, and provided with a magnet the armature of which closes same; and a control circuit connected across said variable voltage line and electrically connected to said magnet for energizing same; all substantially as and for the purposes shown and described.

2. In a system of electric current control, in combination, a positive lead transmitting a constant voltage current; and a positive lead transmitting a variable voltage current; and a negative lead, common to said constant and variable voltage leads and completing their respective circuits; and a distribution circuit connected across said constant voltage line, and provided with a magnet the armature of which closes same; and a control circuit connected across said variable voltage line electrically connected to said magnet for energizing same; and an electric current motor the circuit of which is provided with a resistance coil, a rheostat and a pole-changer, for reversing the polarity of said field and operating said motor; all substantially as and for the purposes shown and described.

3. A door closing apparatus consisting of an electric current motor, provided with a resistance coil, a rheostat and a pole-changer inserted in the circuit of said motor; in combination with a magnet the armature of which is provided with contacts for closing

the operating circuit of said motor, and energized by a variable voltage circuit; and a circuit-breaker operated by the movement of the door being closed; all substantially as 5 and for the purposes shown and described.

4. A door-closing apparatus consisting of the leads of an electric current circuit for supplying the energy for its operation; an electrically driven motor provided with a 10 train of speed-reducing gear-wheels terminating in a pinion engaging with a gear-rack attached to the door to be closed; and a resistance coil, a rheostat and a pole-changer inserted in the supply-circuit and in the motor-circuit for reversing the rotation of said 15 motor; and leads for a constant voltage electric current circuit for transmitting current from said leads of the current-supply to said motor; and an electric magnet inserted in the 20 operating circuit of said motor and provided with an armature and contact points for closing said motor circuit, and energized by a variable voltage circuit; and a variable voltage electric current circuit for transmitting 25 current from the leads of said current-supply to said magnet for energizing same, and provided with a rheostat for obtaining the variation of its voltage; and a circuit-breaker inserted in said energizing circuit of said 30 magnet and operated by the movement of the door being closed; all substantially as and for the purposes shown and described.

5. An electro-mechanical device consisting of a magnet provided with electric contact points, in combination with an armature 35 supported in a movable position by a guide-rod attached to the core of said magnet and having its opposite end threaded and fitted with an adjustable nut for varying the width of the air-gap between said armature and the 40 core of said magnet; and a contact ring attached to but electrically insulated from said armature for electric current circuit closing through its contact with said contact points; all substantially as and for the purposes 45 shown and described.

6. An electro-mechanical device consisting of a magnet provided with electric contact points, in combination with a weighted armature supported in a movable position 50 by a guide-rod attached to the core of said magnet; and a contact ring attached to but electrically insulated from said armature for circuit closing through its contact with said contact points; all substantially as and for 55 the purposes shown and described.

In testimony whereof I have hereto signed my name in the presence of two subscribing witnesses.

DAVID R. KNAPP.
